UNITED STATES PATENT OFFICE.

JOSEPH BARDSLEY, OF MONTCLAIR, AND ALBERT J. ROSENTRETER, OF BOONTON, NEW JERSEY; SAID ROSENTRETER ASSIGNOR TO SAID BARDSLEY.

HYDRAULIC BRAKE.

SPECIFICATION forming part of Letters Patent No. 740,513, dated October 6, 1903.

Application filed May 8, 1902. Serial No. 106,489. (No model.)

To all whom it may concern:

Be it known that we, JOSEPH BARDSLEY, a resident of Montclair, Essex county, and ALBERT J. ROSENTRETER, a resident of Boonton, 5 in the county of Morris, State of New Jersey, citizens of the United States, have invented jointly certain new and useful improvements in Hydraulic Brakes, of which the following is a specification.

10 The invention relates to improvements in brake mechanism for cars and other vehicles; and it consists in the novel features, arrangements, and combinations of parts hereinafter described, and particularly pointed out in the 15 claims.

The object of the invention is to produce a more efficient, convenient, and simple hydraulic brake than those heretofore constructed.

20 We have presented our invention in this application as comprising a liquid-containing tank, box, or casing within which are arranged a series of pumps to be operated from the car-axle, a power-cylinder containing a piston to be moved by the pressure of the liquid forced 25 into the lower end of the cylinder by said pumps and which when moved will set in motion certain intermediate levers for applying the brakes, a controller rod or device for manual operation for determining the action of 30 the liquid within the power-cylinder, a clutch mechanism by which under the action of said controller device the power of the car-axle may be cut off from the said pumps, and a 35 weighted valve capable of regulation and adjustment for permitting the automatic exhaust of any excess of liquid which may by means of said pumps be forced into the said power-cylinder. The tank, box, or casing 40 containing the features above mentioned will be secured to the truck-frame or other support, and the motion of the car-axle will through intermediate gearing be communicated to the power or pumping shaft within 45 said box or casing for the purpose of actuating the pumps and applying the brakes.

The essential features of our invention are inclosed within the liquid-containing box or casing, and it is an important feature of our 50 invention that the box or casing is a self-contained apparatus holding the liquid and in-

closing the pumps, the power-cylinder, valves, and other necessary features.

In carrying out our invention there is an absence of circulating-pipes for the liquid, these 55 pipes and other connections being dispensed with.

In accordance with our invention the liquid-containing box or casing forms a chamber within which the liquid is at all times 60 held. The operative parts inclosed within the tank or casing remain at rest during the usual travel of the car and are only set into action when it is desired that the brakes shall be applied.

The invention and satisfactory means for carrying the same into effect will be fully understood from the detailed description hereinafter presented, reference being had to the accompanying drawings, in which—

Figure 1 is a side elevation, partly broken away and partly in section, of a car-brake mechanism constructed in accordance with and embodying the invention, the car wheel, axle, brake-shoe, and brake-rigging being of 75 ordinary construction and the features comprising the invention proper being shown in vertical section on the dotted line 1 1 of Fig. 5. Fig. 2 is an enlarged detached sectional view through the power-shaft on the dotted 80 line 2 2 of Fig. 5 and illustrates a part of the clutch mechanism connected with said shaft. Fig. 3 is a like view of same on the dotted line 3 3 of Fig. 5. Fig. 4 is an enlarged vertical transverse section through the mechanism embodying our invention, said section being taken on the dotted line 4 4 of Fig. 6. Fig. 5 is a top view, partly broken away and partly in horizontal section, of the liquid-containing casing and features therein embraced 90 within our invention. Fig. 6 is a like section of same on the dotted line 6 6 of Fig. 1. Fig. 7 is a detached view, partly broken away, looking downward upon the power-cylinder within the liquid-containing casing. Fig. 8 95 is a detached central vertical section through the lower portion of the controlling-rod for the brake mechanism, and Fig. 9 is a side elevation of same.

In the drawings, 15 denotes the usual car- 100 axle; 16, a car-wheel; 17, a brake-shoe; 18, a customary form of brake-rigging, and 19 a

connecting-rod by which the brake-rigging may be connected with a bell-crank lever 20, which is to be operated in the manner hereinafter described by the means comprising our present invention, said means being largely contained within a box or casing 21, which will have a cover or cap 22 and be provided at one side with suitable flanges 23 23, containing holes, as shown in Fig. 1, to receive the bolts or screws by which the casing 21 may be conveniently secured to the truck-frame or other support in suitable relation to the car-axle 15.

The body of the box 21 will preferably be formed in one integral casting and will have a dished bottom 24, provided with an outlet-nozzle 25, controlled by a valve 26, this outlet-nozzle 25 being provided merely for the purpose of cleaning out the bottom of the box or casing 21 whenever desired.

Within the box or casing 21 is secured the horizontal frame 27, the latter being held at its corners by means of screws 28, as shown in Fig. 6, and forming between its lower surface and the upper surface of the bottom of the box or casing 21 a chamber 29, as shown in Fig. 1, which opens freely into the general chamber formed within the box or casing 21.

The frame 27 has formed integrally with it the series of pump-cylinders 30 and power-cylinder 31, the said cylinders 30 at their lower ends all being connected by the ports or passages 32 with the base of the power-cylinder 31, whereby the liquid may be forced from said cylinders 30 into said cylinder 31, as hereinafter explained. Within the base of the power-cylinder 31 the terminating ends of the ports or passages 32 are provided with ball-valves 33, which when in their lower position, as shown in Fig. 1, close the said ports 32, but which are capable of being elevated from their seats by the flow of the liquid from the pump-cylinders 30 and through the ports 32 in order to enable the liquid passing through said ports to enter the power-cylinder 31 and act to move the piston 34 within said cylinder in an upward direction. Above the ball-valves 33 there is provided in the base of the power-cylinder 31 a piece of wire-cloth or perforated metal 35 to limit the upward motion of the ball-valves 33 and to confine said valves to their respective chambers. The frame 27 is also formed with the vertical sleeves 36 and 37, which are connected by a port or passage 38 with the base of the power-cylinder 31 and which respectively receive the lower end of the safety valve-rod 39 and controller-rod 40, the sleeve 36 being provided with the vertical port 41, leading upward from the port 38 to the general chamber within the box or casing 21 and normally closed at its upper end, where a valve-seat is formed, by the lower conical end of said valve-rod 39. The lower end of the controller-rod 40 is formed with the right-angular aperture or passage 42, which is adapted to be moved into and out of communication with the port or

passage 38, leading from the power-cylinder 31. The vertical member of the aperture 42 in the lower end of the controller-rod 40 is always in communication with an aperture 43, (see Fig. 4,) passing downward through the frame 27 to the chamber 29 below said frame. When the controller-rod 40 is in the special position shown in Fig. 4, any liquid entering the power-cylinder 31 would find a free passage through the port 38, aperture 42, and aperture 43, and hence under such condition the liquid entering the power-cylinder 31 would have no appreciable effect upon the piston 34 therein. When it is desired that the liquid entering the cylinder 31 shall elevate the piston 34 for the purpose of applying the brakes, the aperture 42 in the controller-rod 40 will be turned so that the horizontal member of said aperture 42 shall pass out of register with the port or passage 38, and thereby cutting off the escape from the power-cylinder 31 and enabling the liquid pumped into the base of said cylinder through the passages or ports 32 to elevate the piston 34 in the manner and with the effect herein-after explained. The frame 27, secured in the base of the box or casing 21, thus comprises the series of pumping-cylinders 30, the power-cylinder 31 and ports 32, leading from said pumping-cylinders to said power-cylinder, the sleeve 36, containing the port or safety vent-passage 41, the sleeve 37 to receive the lower end of the controller-rod 40, the port or passage 38, leading from the power-cylinder into the said sleeve 37, and the aperture 43, leading downward from said sleeve 37 into the chamber 29 below the frame 27.

Within the pumping-cylinders 30 are provided the vertically-reciprocating plungers 44, Fig. 1, containing the vertical opening 45 and valve-chamber 46, the latter confining a ball-valve 47, which when the plungers 44 move downward against the liquid below them will be elevated and close the openings 45, thereby compelling the liquid below the plungers 44 to pass through the ports or passages 32 to the power-cylinder 31. When the plungers 44 are either stationary or moving upward, the ball-valves 47 will descend into the enlarged chambers 46, and at such time the liquid within the casing or box 21 may flow downward through the openings 45 and pass below the said plungers 44. The box or casing 21 will be supplied with oil or other suitable liquid to a height somewhat below the joint formed between the cover and body of the box, and hence during the upward motion of the plungers 44 the oil or other liquid will be enabled to pass downward through the openings 45 in said plungers and be by the latter forced through the ports or passages 32 into the lower end of the power-cylinder 31. The plungers 44 receive their motion from a transverse shaft 48, mounted upon the upper portions of the body of the box or casing 21 and extending at one end outward beyond the side of said box or casing, where said

shaft 48 is provided with the sprocket-wheel 49, the latter being connected by the sprocket-chain 50 with a sprocket-wheel 51, connected with the car-axle 15, the power from said axle 15 being utilized at the proper time to drive the shaft 48 and actuate the pump-plungers 44. The plungers 44 will be connected with the shaft 48 by suitable driving mechanism, and in the present instance we provide eccentricities 52 upon the shaft 48 and pivotally connect the plungers 44 with the rods 53, connected with said eccentricities, said eccentricities being set at different angles instead of parallel with one another in order that the plungers 44 may not all ascend and descend in unison and that some one of said plungers during the use of the mechanism may be performing a downstroke.

The power-shaft 48 for the pumps will preferably remain idle except when it is desired to apply the brakes, there being no necessity for said pumps being kept in motion during the entire travel of the car, and hence we provide clutch mechanism (shown in Figs. 2 and 3) which will be hereinafter explained and which, except when otherwise desired, as during the application of the brakes, will allow the sprocket-wheel 49 to turn idly upon the end of the shaft 48, the latter remaining at rest.

If for any reason it would be desired that the shaft 48 remain in motion during the entire travel of the car, the pump-plungers 44 could run idly—that is, without applying the brakes—by maintaining an open passage from the lower end of the power-cylinder 31 to the chamber 29 below the frame 27; but it is preferable that the power-shaft 48 and pump-plungers 44 remain at rest except when it is desired to apply the brakes.

The piston 34 within the power-cylinder 31 is secured upon the lower end of the vertical piston-rod 152, which extends upwardly through a bearing-sleeve 153, provided in the top of the cover 22 for the casing 21, and above the said cover 22 the upper end of the rod 152 is connected by a link 54 with the bell-crank lever 20, hereinabove referred to, the said lever 20 being mounted upon a suitable standard or bracket 55 and connected with the rod 19 for the brake-rigging, as shown in Fig. 1.

When the piston 34 is forced upwardly, its rod 152 will turn the bell-crank lever 20 and cause the rod 19 to move the brake-shoe 17 against the car-wheel 16, and when the piston 34 descends its rod 152 will effect a reverse movement of the lever 20 and rod 19 and release the brake-shoe. The upward motion of the piston 34 will be effected by the action of the pumps in forcing the liquid below said piston 34, and the downward motion of the piston 34 will be effected by means of a coiled spring 56, arranged upon the rod 152 intermediate the upper surface of said piston 34 and the lower end of the bearing-sleeve 153.

The valve-rod 39 is held downward upon

its seat, closing the port 41 in the sleeve 36, by means of a coiled spring 57, Fig. 4, which is confined between a collar 58, fastened on said rod, and the lower end of the adjustable sleeve 59, the latter having an exterior screw-thread engaging a screw-threaded aperture in the cover 22. The upper end of the rod 39 enters the sleeve 59 and is guided in its movement thereby, and the force of the said spring 57 may be increased or diminished by the adjustment downward or upward of the said sleeve 59, the upper end of the latter being exposed, so as to be conveniently operated. The rod 39 will always remain in its lower position except when the pressure of the liquid against the lower surface of the piston 34 is excessive and sufficient to elevate the lower end of the rod 39 from its seat, this excess of pressure being then relieved by the passage of a part of the liquid upward through the port 41. The valve-rod 39 has an automatic operation, being forced downward against its seat by means of the spring 57 and upwardly from its seat by the pressure of the liquid entering the power-cylinder 31 and filling the ports or passages 38 and 41.

The controller-rod 40 by its position determines when the liquid shall act against the piston 34, since when the said rod 40 is in the special position shown in Fig. 4 its aperture 42 establishes a free outlet from the lower end of the power-cylinder 31, and hence when the brakes are to be applied the controller-rod 40 must be moved to carry its aperture 42 away from the passage 38, leading from the power-cylinder 31. The controller-rod 40 also determines by its position whether the power from the car-axle shall be communicated to the pump or power shaft 48, and the said controller-rod 40 is to be manually operated by the motorman in charge of a car, the upper end of said rod 40 being equipped with a crank-arm 60, which may be either directly or indirectly operated by the motorman to turn the rod 40 axially, the axial turning of said rod 40 determining the position of the aperture 42 in the lower end of said rod with respect to the passage 38, leading from the power-cylinder 31, and also determining, as will be hereinafter explained, the action of the clutch mechanism with respect to the pumping-shaft 48.

The clutch mechanism for the power or pumping shaft 48 is more clearly illustrated in Figs. 1, 2, 3, and 5, and the purpose of this clutch mechanism is to normally permit the sprocket-wheel 49 to rotate freely without turning the shaft 48. The sprocket-wheel 49 is fastened to a sleeve 61, Fig. 3, which is free upon the end of the shaft 48 and carries at its inner end the toothed wheel 62, the latter and said sleeve 61 and sprocket-wheel 49 thus being connected together and capable of rotation upon without affecting the shaft 48. Upon the shaft 48, adjacent to the toothed wheel 62, is secured the guide-block 63, Fig. 2, which is held in place against the adjoin-

ing eccentric 52 by means of the screws 64 and upon which block 63 is placed the sliding frame 65, having at one end the tooth 66 and at its other end the projection 67. Within 5 in the frame 65 is disposed the coiled spring 68, the latter serving to normally hold the frame 65 in position, as illustrated in Figs. 2 and 3, whereby the tooth 66 of said frame becomes normally projected against the toothed 10 wheel 62 for the purpose of engaging the same and locking the shaft 48 with the toothed wheel 62, sleeve 61, and sprocket-wheel 49, and when the parts are thus connected, which is the condition when the brakes are to be 15 applied, the motion of the sprocket-wheel 49 will be communicated to the shaft 48, with the result that the pump-plungers 44 will be set into action. When the frame 65 is moved against the stress of the spring 68, its tooth 20 66 will be withdrawn from the toothed wheel 62, and at such time and under such condition the shaft 48 will be free of the sprocket-wheel 49, and the latter may turn without rotating said shaft.

25 During the ordinary travel of the car the frame 65 will be held free from engagement with the toothed wheel 62 by means of the projecting end 69, Fig. 5, of the pivoted arm 70, said end of said arm 70 being then held 30 against the projection 67 of the frame 65 and pressing the latter against the stress of the spring 68 by means of the cam 71, secured upon the controller-rod 40 and having a slot, as shown in Fig. 5, in engagement with a pin 35 72, rigidly connected with the said arm 70. When the car is in normal motion, the controller-rod and cam 71 will be in the position in which they are illustrated in Figs. 4 and 5, said cam at such time operating through 40 the arm 70 to maintain the clutch-frame 65 free of the toothed wheel 62 and allowing the sprocket-wheel 49 to rotate without affecting the shaft 48.

When it is desired to apply the brakes, the 45 controller-rod 40 will be turned to carry its lower aperture 42 from the passage 38, leading from the power-cylinder 31, and to relieve the arm 70 from the frame 65 of the clutch mechanism, said frame 65 under the force of 50 the spring 68 then automatically passing into engagement with the toothed wheel 62 to secure the movement of the pumping-shaft 48 with the sprocket-wheel 49. When it is desired to release the brakes, the controller-rod 55 55 40 will be reversed in motion and restore its lower aperture 42 into communication with the passage 38, leading from the power-cylinder 31, the cam 71 being at the same time returned to its initial position for the purpose 60 of moving the arm 70 against the clutch-frame 65, and thereby releasing said frame from the toothed wheel 62.

The operation of the mechanism hereinbefore described will be largely understood 65 from the explanations hereinbefore given, and but brief further description of the operation seems necessary. The box or casing

21 will be partly filled with liquid, preferably oil or a mixture of alcohol and glycerin, and in the initial condition of the parts the 70 shaft 48 will be held free of the sprocket-wheel 49 and the aperture 42 in the lower end of the controller-rod 40 will establish a communication between the passage 38 and the general chamber within the casing or 75 box 21. When it is desired to apply the brakes, the rod 40 will be turned to allow the clutch mechanism to lock the shaft 48 and sprocket-wheel 49 together and to remove the aperture 42 at the lower end of the 80 said rod 40 from communication with the aforesaid passage 38. Under this condition of the parts the pump-plungers 44 will be set in motion, and the liquid passing downward through them will be driven by them through 85 the passages or ports 32 into the lower end of the power-cylinder 31, with the result of elevating the piston 34 and piston-rod 152 and through the bell-crank lever 20 effecting the application of the brakes. Any excess 90 of liquid pumped into the power-cylinder 31 will be relieved through the passages or ports 38 and 41, the valve-rod 39 yielding upwardly under an excess of pressure in the power-cylinder 31 to permit a part of the liquid to escape 95 into the general chamber of the box or casing 21. When it is desired to release the brakes, the controller-rod 40 will be operated to free the clutch-frame 65 from the toothed wheel 62 and reestablish its aperture 42 in 100 line with the passage 38, the power of the sprocket-wheel 49 being thus cut off from the pumping-shaft 48 and the liquid below the piston 34 in the power-cylinder 31 being permitted to escape during the descent of 105 said piston through the passage 38, aperture 40, and aperture 43, said piston 34 descending by gravity supplemented by the force of the spring 56. In order to effect a gradual cutting off of the aperture 42 at the lower 110 end of the controller-rod 40 from the passage 38 and also a gradual reestablishment of communication between said aperture and said passage, we groove transversely the surface of the rod 40 adjacent to the entering end of 115 said aperture 42, as denoted at 73 in Figs. 8 and 9, the aperture 42 not being entirely cut off from the passage 38 until the groove 73 ceases to connect with said passage.

In the application of the brake mechanism 120 hereinbefore described to, for instance, an electric car of ordinary character we would deem it desirable that the controller-rod 40 and cam 71 should be moved by or concurrently with the usual operating-handle on 125 cars, so that the said rod 40 and cam 71 shall have moved sufficiently during the movement of said handle to cut off the electric power to allow the clutch-frame 65 to act and set the pumping-shaft 48 in motion and that a 130 slight further continued movement of said handle on the car should result in the aperture 42 at the lower end of the controller-rod 40 being moved out of communication with

the passage 38, leading from the power-cylinder 31, and to this end we make the slot in the cam 71 in two sections, numbered, in Fig. 5, 74 and 75, respectively, 76 denoting the intermediate point between said sections 74 and 75. With this construction of cam 71 the section 74 of its slot while moving in one direction over the pin 72 will move the arm 70 from the clutch-frame 65 and allow the latter to act and set the shaft 48 in motion, and this movement of the cam 71 will take place when the motorman is cutting off the electric power from his car. The continued motion of the rod 40 and cam 71 will cause the section 75 of the cam-slot to pass along the pin 72 without acting on the arm 70, said section 75 of said slot being on the true arc of a circle and simply passing along the pin 72 without moving the same. During this latter part of the movement of the cam 71, or while the section 75 of its slot is passing along the pin 72, the rod 40 will move its aperture 42 entirely out of communication with the passage 38, whereby the free circulation of the liquid will be prevented and the liquid driven through the passages 32 by the pump-plungers 44 will be caused to act against and elevate the piston 34 for applying the brakes. During the reverse motion of the cam 71 back to the position in which it is shown in Fig. 5 the section 75 of its slot will first move along the pin 72 without acting upon the arm 70 and the aperture 42 at the lower end of the controller-rod 40 will gradually move back into communication with the passage 38, and when in this reverse movement of the cam 71 the section 74 of its slot passes against the pin 72 the walls of this section 74, acting as a cam, will move the arm 70 so that its front projecting end 69 will return to the position in which it is shown in Fig. 5, where it will meet and press inward the curved projection 67 on the end of the clutch-frame 65, thereby compressing the spring 68 and moving the tooth 66 of said frame from the toothed wheel 62, the pump-shaft 48 then by reason thereof ceasing to rotate. When the electric power of a car is cut off, the car-wheels, due to momentum, will continue in motion, and hence after the electric power has been cut off there will be sufficient continuing movement in the car-axle 15 for operating the pump-plungers 44 and effecting the application of the brakes. With the form of cam 71 shown in Fig. 5 the clutch-frame 65 is moved into operative position while the electric power on the car is being cut off, and then the continued movement of the controller-rod 40 cuts off the escape-passage 38 for the liquid and the pump-plungers 44 are enabled to force the liquid against the piston 34 and effect the application of the brakes. The cam 71 is directly over the end 69 of the pivoted arm 70, and said end of said arm 70 rests freely upon a shelf or bracket 77, fastened to the inner wall of the box or casing 21, the latter being simply a convenient tank

for containing the liquid and the operative parts utilized in connection therewith.

The tapered groove 73 at the entering end 70 of the aperture 42 in the lower end of the controller-rod 40 is to provide for gradually shutting off the outlet-passage 38 and correspondingly diverting the pressure of the liquid against the power-piston, so as to gradually apply the power to the brake.

The invention is not confined to its employment in connection with electric cars, but is well adapted for such use; nor is the invention limited to all of the features and details shown and described, some of which may be omitted and others modified within the scope of our invention as claimed.

What we claim as our invention, and desire to secure by Letters Patent, is—

1. A hydraulic brake mechanism comprising a casing containing a body of liquid, a perpendicular pump disposed within said casing and submerged in said liquid, a crank-shaft 48 placed above said pump and parallel to the axle of the vehicle, means for driving said shaft from said axle, and means for driving the piston of said pump from said crank-shaft, combined with a power-cylinder, a port or passage connecting said power-cylinder with the pump-cylinder for enabling said pump to drive the liquid into said power-cylinder, a piston within said power-cylinder to be acted upon by the pressure of said liquid and connected with the brake connections for actuating the latter, and means for manually controlling the operation of said pump and said piston; substantially as set forth.

2. A hydraulic brake mechanism comprising a casing containing a body of liquid, a perpendicular pump disposed within said casing and submerged in said liquid, a crank-shaft 48 placed above said pump and parallel to the axle of the vehicle, means for driving said shaft from said axle, and means for driving the piston of said pump from said crank-shaft, combined with a power-cylinder also disposed within said casing, a port connecting said power-cylinder with the pump-cylinder for enabling said pump to drive the liquid into said power-cylinder, a piston within said power-cylinder to be acted upon by the pressure of said liquid and having a rod projecting from said casing and connected with the brake connections for actuating the latter, an outlet-port leading from said power-cylinder to the general chamber of said casing, and a controller-rod to be manually operated and adapted for opening and closing said outlet-port; substantially as set forth.

3. A hydraulic brake mechanism comprising a casing containing a body of liquid, a perpendicular pump disposed within said casing and submerged in said liquid, a crank-shaft 48 placed above said pump and parallel to the axle of the vehicle, means for driving said shaft from said axle, and means for driving the piston of said pump from said crank-shaft, combined with a power-cylinder

also disposed within said casing, a port connecting said power-cylinder with the pump-cylinder for enabling said pump to drive the liquid into said power-cylinder, a piston within said power-cylinder to be acted upon by the pressure of said liquid and having a rod projecting from said casing and connected with the brake connections for actuating the latter, an outlet-port leading from said power-cylinder to the general chamber of said casing, a controller-rod to be manually operated and adapted for opening and closing said outlet-port, and a weighted valve and port for permitting any excess of liquid in said power-cylinder to relieve itself therefrom; substantially as set forth.

4. A hydraulic brake mechanism comprising the holding-casing for containing a free body of liquid, a pump disposed within said casing and immersed in said body of liquid, a port leading from the chamber of the pump to said free body of liquid, an automatic valve controlling said port, and power-transmitting means connected with the car-axle for operating said pump to act upon a part of said liquid, combined with a power-cylinder also disposed within said casing, a port connecting said power-cylinder with the pump-cylinder for enabling said pump to drive the liquid into said power-cylinder, a piston within said power-cylinder to be acted upon by the pressure of said liquid and having a rod projecting from said casing and connected with the brake connections for actuating the latter, an outlet-port leading from said power-cylinder to the general chamber of said casing, a controller-rod to be manually operated and adapted for opening and closing said outlet-port, and means intermediate said controller-rod and said pump and operable from said rod for determining when said pump shall act; substantially as set forth.

5. A hydraulic brake mechanism comprising the holding-casing for containing a free body of liquid, the pump disposed within said casing and immersed in said body of liquid, a port leading from the chamber of the pump to said free body of liquid, an automatic valve controlling said port, the driving-shaft for said pump, power-transmitting means connected with the car-axle for rotating said shaft to set the pump into action, and the clutch connected with said shaft for cutting off the power from same, combined with a power-cylinder also disposed within said casing, a port connecting said power-cylinder with the pump-cylinder for enabling said pump to force the liquid into said power-cylinder, a piston within said power-cylinder to be acted upon by the pressure of said liquid and having a rod projecting from said casing and connected with the brake connections for actuating the latter, and means for manually controlling the position of said clutch and thereby the operation of said pump and piston; substantially as set forth.

6. A hydraulic brake mechanism comprising

the holding-casing for containing a free body of liquid, the pump disposed within said casing and immersed in said body of liquid, a port leading from the chamber of the pump to said free body of liquid, an automatic valve controlling said port, the driving-shaft for said pump, power-transmitting means connected with the car-axle for rotating said shaft to set the pump into action, and the clutch connected with said shaft for cutting off the power from same, combined with a power-cylinder also disposed within said casing, a port connecting said power-cylinder with the pump-cylinder for enabling said pump to force the liquid into said power-cylinder, a piston within said power-cylinder to be acted upon by the pressure of said liquid and having a rod projecting from said casing and connected with the brake connections for actuating the latter, an outlet-port leading from said power-cylinder, and the controller-rod to be manually operated and adapted for opening and closing said outlet-port and for controlling the position of the clutch and thereby the operation of said pump; substantially as set forth.

7. A hydraulic brake mechanism comprising a casing containing a body of liquid, the pump disposed within said casing, the driving-shaft for said pump, means for rotating said shaft to set the pump into action, and comprising the driven wheel freely mounted on said shaft, the toothed clutch-wheel also normally free upon said shaft and connected with said driven wheel, the sliding clutch-frame keyed upon said shaft and having the tooth to engage said clutch-wheel, the spring normally acting to hold said frame in engagement with said clutch-wheel, and an operating-arm adapted to be moved into a position to engage said clutch-frame and effect the disengagement of same from said clutch-wheel, combined with a power-cylinder also disposed within said casing, a port connecting said power-cylinder with the pump-cylinder for enabling said pump to force the liquid into said power-cylinder, a piston within said power-cylinder to be acted upon by the pressure of said liquid and having a rod projecting from said casing and connected with the brake connections for actuating the latter, an outlet-port leading from said power-cylinder, and the manually-operable controller-rod connected with said operating-arm for moving the same with respect to said clutch-frame and adapted for opening and closing said outlet-port; substantially as set forth.

8. A hydraulic brake mechanism comprising the holding-casing for containing a free body of liquid, the pump immersed within said body of liquid within said casing and comprising the cylinder and valved plunger therein, the driving-shaft for said pump, the crank and rod connecting said shaft and plunger within said casing, and power-transmitting means connected with the car-axle for rotating said shaft, combined with a power-cylinder

der also disposed within said holding-casing, the valved port connecting said power-cylinder with the pump-cylinder for enabling said pump to drive the liquid into said power-cylinder, a piston within said power-cylinder to be acted upon by the pressure of said liquid and having a rod projecting from said casing and connected with the brake connections for actuating the latter, and means for manually controlling the operation of said pump; substantially as set forth.

9. A hydraulic brake mechanism comprising a casing containing a body of liquid, the perpendicular pumps disposed within said casing, the crank-shaft 48 for operating said pumps, and means for driving said shaft, combined with the power-cylinder also disposed within said casing, the independent valved ports connecting said power-cylinder with the pump-cylinders for enabling said pumps to drive the liquid into said power-cylinder, a piston within said power-cylinder to be acted upon by the pressure of said liquid and having a rod connected with the brake connections for actuating the latter, an outlet-port leading from said power-cylinder, and a controller-rod to be manually operated and adapted for opening and closing said outlet-port; substantially as set forth.

30 10. A hydraulic brake mechanism comprising the series of pumps, the shaft having the differently-set cranks connected with the pump-rods for operating the same, and power-transmitting means connected with the car-35 axle for rotating said shaft, combined with the power-cylinder, the valved ports connecting said power-cylinder with the pump-cylinders for enabling said pumps to drive the liquid into said power-cylinder, the piston 40 within said power-cylinder to be acted upon by the liquid and having a rod connected with the brake connections for actuating the latter, and means for manually applying the power to and cutting the same off from said 45 pumps for controlling the operation of said piston and determining when said pumps shall act; substantially as set forth.

11. A hydraulic brake mechanism comprising the holding-casing for containing a free 50 body of liquid, a pump immersed in said body of liquid for acting on a part of said liquid, a port leading from the chamber of the pump to said free body of liquid, an automatic valve controlling said port, power-transmitting 55 means connected with the car-axle for operating said pump, a clutch for connecting said operating means with said pump, and means for manually controlling said clutch and thereby determining when said pump shall 60 act to effect the application of the brakes, combined with a power-cylinder to receive the pumped liquid, a controlled port leading from said power-cylinder to the holding-chamber of said casing, means for manually controlling 65 said port, and a piston in said power-cylinder and connected with the brake-shoe

connections for operating the latter; substantially as set forth.

12. A hydraulic brake mechanism comprising a casing for containing a body of liquid, 70 the power-cylinder freely open at one end therein, a piston within said cylinder to be acted upon by said liquid and having a rod connected with the brake connections for actuating the latter, and the port leading to 75 said cylinder, combined with means disposed within said casing and operable from without the same for forcing a part of said liquid through said port into said cylinder for moving said piston, the outlet-port from said cylinder to the general chamber of said casing, and the controller-rod for manual operation and adapted for opening and closing said port and for controlling the action of the means for driving the liquid into the power-cylinder, said controller-rod having the port 80 through it for communication with said outlet-port, and said rod having the tapered groove at the entrance to its port; substantially as set forth.

90 13. A hydraulic brake mechanism comprising the casing for containing a body of liquid, and the frame secured within said casing and carrying the pump-cylinder and the power-cylinder, and said frame being provided with 95 the valved port leading from the pump-cylinder to the power-cylinder and the outlet-port leading from the power-cylinder to the general chamber of said casing, combined with the valved plunger within said pump-cylinder, the pivoted rod connected with said plunger, means for operating said rod, the piston within said power-cylinder and having a rod connected with the brake connections for actuating the latter, the controller-rod seated in said frame and adapted for 100 opening and closing said outlet-port, the relief-port in said frame for preventing excessive pressure in said power-cylinder, and the weighted valve for said relief-port; substantially as set forth.

14. A hydraulic brake mechanism comprising a pump, a power-cylinder connected therewith, and a piston within said cylinder and connected with the brake connections for actuating the latter, combined with power-transmitting means connected with the car-axle for actuating the said pump, and a single manually-controlled lever mechanism adapted on the earlier part of its movement 115 to set the pump into operation idly without the circulating liquid then affecting the brakes and on its further movement to control and direct the force of the pumped liquid against the power-piston; substantially as set forth.

Signed at New York, in the county and State of New York, this 7th day of May, A. D. 1902.

JOSEPH BARDSLEY.

ALBERT J. ROSENTRETER.
